Patented June 7, 1904.

UNITED STATES PATENT OFFICE.

HENRY A. WEIHMAN, OF PHILADELPHIA, PENNSYLVANIA, ASSIGNOR TO JOHN F. SIMONS AND THOMAS MADDOCK, OF PHILADELPHIA, PENNSYLVANIA, FREDERICK M. SIMONS, OF SWARTHMORE, PENNSYLVANIA, AND EDWIN S. SIMONS, OF ORANGE, NEW JERSEY, COPARTNERS TRADING AS SIMONS BROTHER & COMPANY AT PHILADELPHIA, PENNSYLVANIA.

DESIGN FOR A BACK FOR MIRRORS, BRUSHES, OR SIMILAR ARTICLES.

SPECIFICATION forming part of Design No. 36,952, dated June 7, 1904.

Application filed May 3, 1904. Serial No. 206,256. Term of patent 3½ years.

To all whom it may concern:

Be it known that I, HENRY A. WEIHMAN, a citizen of the United States, residing at Philadelphia, Philadelphia county, State of Pennsylvania, have invented a new, original, and ornamental Design for the Backs of Mirrors, Brushes, or Similar Articles, of which the following is a specification, reference being had to the accompany drawing, forming part thereof.

The figure is a plan view of a back for a

mirror, brush, or similar article, showing my new design.

What I claim as new, and desire to secure by Letters Patent, is—

The ornamental design for a back for mirrors, brushes or similar articles, as shown.

HENRY A. WEIHMAN.
